Patented Oct. 11, 1921.

FIG. 1.

FIG. 2.

Inventor
Walter J. Young

UNITED STATES PATENT OFFICE.

WALTER J. YOUNG, OF ST. LOUIS, MISSOURI.

INDIVIDUAL-RECORD EJECTOR FOR GRAPHOPHONE-CABINETS.

1,393,065.

Specification of Letters Patent.

Patented Oct. 11, 1921.

Application filed September 17, 1920. Serial No. 410,910.

To all whom it may concern:

Be it known that I, WALTER J. YOUNG, a citizen of the United States, and resident of St. Louis, Missouri, have invented certain new and useful Improvements in an Individual-Record Ejector for Graphophone-Cabinets, of which the following is a specification.

This invention relates to improvements in an individual record ejector for graphophone cabinets, and has for its object a mechanism located conveniently beneath each record compartment for advancing the record and permitting it to project a short distance in front of the compartment so that the same can be readily and easily gripped for placing it in position on the graphophone.

The invention consists of a lever mechanism operated by a push key which presses the record forward out of its original nesting place and for making it to project beyond the front surface of its compartment.

Figure 1, is a perspective view of a graphophone cabinet showing the record compartment with one of the records ejected.

Fig. 2, is a cross sectional view showing the location of the mechanism in its relative position with the record.

Fig. 3, is a detail perspective view of the ejecting mechanism detached from the cabinet.

Referring to the drawings in detail 4 indicates an ordinary graphophone cabinet, 5 the disk record compartment. This compartment is provided with a plurality of division partitions 6 between which is placed on edge a disk record.

On the bottom and in front of the plurality of partitions is placed a cross strip 7 which is provided with a row of holes 8 and through these holes project the operating rods 9, the forward end of each rod provided with a push button or head 10.

The opposite end 11 of the rod 9 is pivotally attached to an ejector 12 consisting of an arm hingedly or pivotally mounted on a supporting rod 13 which runs through the entire series of partitions and the full

length of a cabinet. These ejectors are made of the same width as the space between the partitions 6 and act as a partial support for the edge of the disk record.

In Fig. 2, the disk record is shown in solid

and indicated by the numeral 14, it has bearing on the ejector 12, on the rear wall 15 of the cabinet and on a hurdle pivot 16 which is in the form of a rod running through the entire series of partitions.

On the inside of the front strip 7 and between each one of the partitions I place a wedge block 17, this acts as a support for the disk record when the same has been ejected by the means of the operating mechanism, and when so ejected it will suit the 65 position as shown by the dotted lines A.

In operating the ejector the operator merely pushes against the button 10 which will operate the ejector in the position as shown by dotted lines B pushing the record forward until it passes its own center and when riding over the hurdle pivot 16, it will then by its own gravity assume the position as shown by dotted lines A.

After the disk has been removed and 75 played it can then be re-inserted in its own compartment and by pushing it inward its own gravity will have a tendency to throw back the ejector and place the operating mechanism in its normal position.

The essential feature of my invention is to equip a graphophone cabinet with a lever mechanism for ejecting a record disk and place it in such projecting position so that the same can be easily gripped by the 85 fingers and removed from its compartment.

Having fully described my invention what I claim is:

A device of the character described comprising in combination with a graphophone 90 cabinet, a compartment having a plurality of partitions, a pivotally mounted arm located in the bottom of each space between the partitions, a hurdle pivot extended through the entire series of partitions, an 95 operating rod located in each compartment and pivotally connected to the lower end of said pivoted arm, and a supporting wedge located in the forward end for supporting an ejected record.

In testimony whereof, I have signed my name to this specification, in presence of two subscribing witnesses.

WALTER J. YOUNG.

Witnesses:

ALFRED A. EICKS,
B. M. AUSTINE.
